GILBERT WRIGHT, OF PELHAM, NEW YORK.

VALVE AND CONTROLLING MEANS THEREFOR.

1,319,502.

Specification of Letters Patent. Patented Oct. 21, 1919.

Application filed January 4, 1917; Serial No. 140,525.

To all whom it may concern:

Be it known that I, GILBERT WRIGHT, a citizen of the United States, residing at Pelham, in the county of Westchester and State of New York, have invented new and useful Improvements in Valves and Controlling Means Therefor, of which the following is a specification.

The present invention relates to valves for controlling the flow of fluids and is particularly applicable to those which are operated intermittently, that is, are opened and closed automatically at more or less frequent intervals. The general object is to provide a means by which the proportional part of the complete cycle of operations during which the valve remains open, or conversely remains closed, may be regulated and altered at will. A further object is to provide a simple and efficient electromagnetic means in connection with mechanical operating mechanism for operating a valve of the sort above indicated to accomplish the ends indicated. The invention consists therefore in the combination with a valve of operative mechanism for actuating the valve either to open or close the same, or for both opening and closing it, a part of such mechanism being adapted to yield under the actuation of superior force, with further mechanism or means for exerting such superior force in opposition to said yielding means to overcome the valve actuating effort of the latter; said latter or controlling mechanism being adjustable so as to act during a longer or shorter period of time, and being preferably, although not necessarily an electromagnetic device. In the embodiment of the invention presented in this application I have illustrated a positive mechanical actuator for moving the valve in one direction or manner, a yieldable actuator, a spring, for moving it in the opposite direction, an electromagnet for exerting force to overcome the action of said spring, and an automatic circuit interrupter for the magnet a part of which is adjustable to vary the extent of time in each cycle during which the circuit remains closed. Of these drawings,

Figure 1 is a central sectional view of such valve and

Fig. 2 is an elevation of the valve as seen from the right of Fig. 1, with a portion of the mechanism broken away sufficiently to

show the operating shaft and adjusting means. The right hand portion of Fig. 2 is to be read in conjunction with Fig. 1.

The same reference characters indicate the same parts in all the figures.

Referring to the drawings, 10 represents a valve casing or fitting in which there is a tapered seat 11 wherewith a valve 12 of the puppet type co-acts. The stem 13 of this valve passes through a tubular guideway 14 set into the side of the valve fitting as shown, and carries on its outer end, preferably by being detachably threaded thereon, a member 15, part of which is an armature for an electromagnet 16, and another part 15^a is the follower for an operating cam 17 which is fixed to a shaft 18.

The electromagnet 16 referred to is a solenoid magnet which surrounds the tubular guide 14 and is inclosed by a case 19, which latter has a flange 19^a which fits against a flange 10 on the valve fitting, and also forms the base or abutment to support and take the thrust of a spring 20 which surrounds the case 19 and presses against the armature 15; such armature being wide enough to overhang this spring.

A non-magnetic washer 21 is mounted on the pole face of the case 19, that is, the face toward the armature.

Secured to the cam 17, conveniently being integral therewith, although it may be otherwise mounted and arranged to move synchronously with the cam, is a disk 22 which is one of the contact members of a switch or circuit breaker, the contact complementary to which is a stud 23 on the end of a shank 24 which is mounted and movable endwise in an insulating bushing 25 in a bracket 26 on an arm 27. A spring 28 presses the contact button 23 toward the disk 22 as far as permitted by an abutment formed by the binding nuts on the stem 24 coming into contact with a washer 29 surrounding the stem 24 and lying on the end of the bushing 25. The switch thus described is interposed in the circuit of the electromagnet, which is as follows. From the positive pole of a battery 30 or other source of current, a conductor 31 leads to the stem 24 and is clamped thereto by the binding nuts before mentioned. Current passes thence through the disk 22, shaft 18, to an arm 32 which is integral with the valve casing and provides the bearing for shaft 18; thence to the case 19 and the ter-

terminal 33 of the electromagnet, through the winding of the magnet and through a conductor 34 to the negative pole of the battery. The terminal 33 is in contact or in 5 electrical connection with the case 19, but the conductor 34 and the coil are otherwise insulated from such case and from the valve fitting or case.

The foregoing description of the specific 10 circuit is not to be taken as in any sense a limitation of the invention. All that is material to this aspect of the invention is that the electromagnet and the switch described are both in the same circuit so that 15 the switch is adapted to control the electromagnet. Any desired source of electricity may be employed and any form of conductors, whether the same are entirely of wire or are formed in part of the metallic 20 frame members or body of the fitting.

On that part of the arm 32 which forms the bearing for the shaft 18 is an external bearing 35 which is surrounded by a hub 36 on the arm 27, whereby said arm may be 25 swung around the axis of the shaft 18.

It may be assumed that the purposes for 30 which the valve herein described are used require it to be intermittently opened and closed, and that the shaft 18 is therefore maintained in continuous rotation. This being the case, the cam 17 at each rotation presses against the follower 15^a and opens the valve. The current passing through 35 the magnet coil is of such strength, and the coil so designed as to magnetic pull that it is able to overcome the pressure of the spring 20 when the armature is close to the pole face of the magnet case; but is insufficient to overcome the pressure of the 40 spring when the armature is remote from this face, as when the valve is closed. Thus if there is a current flowing through the coil when the armature is brought toward it, the armature is attracted and held after 45 the cam has passed the follower, whereby the valve is held open.

The duration of the held open condition 50 of the valve is governed by the circuit breaker or switch. As long as the contact member 22, which is formed as a sector of a circular disk, continues in contact with the member 23, the magnet remains energetic, but when the disk contact passes away from the contact 23, the magnet loses its power. 55 The length of time that these members remain in contact after the cam passes the follower, determines the length of time that the valve is held open. This period may be varied by swinging the arm 27 about its bearing 35. If swung in the direction in which the cam rotates, it lengthens the duration of the valve opening, having the contrary effect when swung in the opposite direction. Evidently the closing of the 60 circuit by the switch before the cam has opened

the valve has no effect, since the power of the magnet is insufficient to overcome the closing spring when the armature is remote from the magnet; therefore it does not matter whether the circuit is closed a long time or a short time before the cam opens the valve, provided only it is closed at the instant when the valve is widely opened.

The length of time that the switch remains closed after the cam has passed the follower is all that governs the length of time that the valve remains open, and this feature is regulated by the adjustment of the arm 27.

The cycle of operations thus described takes place of course during each rotation of the shaft 18, and comprises successively the opening of the valve by the cam or actuator 17, the holding open of the valve by the electromagnetic means, of which the circuit has already been closed by the circuit breaker or controller 22, after the actuator cam has withdrawn from the valve, the disassembly of the magnetic means by the breaking of the circuit thereof through continued motion of the controller or circuit breaker 22, and the closing of the valve by spring 20. There is of necessity an operating coaction between the valve actuator 17 and the magnet controller 22, each of which has a periodic action in a given sequence to the action of the other, whereby to cause opening of the valve at one point in the cycle, and closing of the valve at another point or time; the valve opening effect being performed by the actuator cam, and the valve closing effect controlled by the magnet controller. Adjustment of the latter, by adjusting the supplemental contact member 23 determines the timing in the cycle of these effects, and therefore that proportional part of the cycle during which the valve remains open.

Instead of the valve being opened by the cam and held open by the electromagnet, it is obvious that the reverse effect might be secured by the mere reversal of the valve and valve seat. In any case the ratio between the length of time during which the valve remains open and the time of the entire cycle, is controlled by the electromagnet and the switch or circuit breaker. Other modifications of the particular mechanism here disclosed will readily occur to the skilled mechanic. All such modifications, whether they consist in substituting other forms of switch, or in causing the magnet to hold the valve closed instead of open, or to hold the follower toward the cam instead of away from it, or whatever they may be, are within the scope of my invention as herein claimed.

A valve having the characteristics hereinbefore defined is capable of a wide variety of uses. Without intending thereby to limit the invention in any way to any use, I will say that one use is in connection with in-

internal combustion engines, wherein the provision for adjustment of the time during which the valve may be held open in the cycle affords very convenient and efficient means for governing the motor without throttling the fuel, and consequently without retaining incombustible burned gases in the combustion space of the engine.

What I claim and desire to secure by Letters Patent is:

1. The combination with a valve and actuating means for moving the same at definite intervals from one position to another position, of magnetic means also operating at definite intervals and adapted when operating to maintain the valve in the second position.

2. The combination with a valve and actuating means therefor arranged and operating to displace the valve from time to time, of magnetic means arranged to hold said valve in its displaced position, and controlling means for said magnetic means arranged and operating to render the latter alternately operative and inoperative within the interval of two successive operations of said actuating means.

3. The combination with a valve, of a periodic actuator operating to move the valve from one position to another and constructed to limit its actuating impulse to a relatively brief duration, magnetic means for retaining the valve in the second position after cessation of said actuating impulse, and a controller for said magnetic means for causing the same to release the valve at given times in cycle with the actuator.

4. The combination with a valve, of a spring acting on said valve with a tendency to close the same, an electro-magnet arranged to exert force tending to open said valve and so placed that the force so exerted is too weak to move the valve from the closed position but is strong enough to hold it in the open position after it has been brought into that position by the application of superior force, and actuating means constructed and arranged to move the valve into the latter position at definite intervals.

5. The combination with a valve, of a spring acting thereon with tendency to move it in one direction and to hold it in one position, an actuator arranged and operating to move the valve in the opposite direction from time to time, an electro-magnet arranged to exert force on said valve in opposition to said spring and tending to shift the valve into a second position, the magnet being so placed that such force is insufficient to overcome the spring and displace the valve from the first position but is great enough to hold the valve in the second position, when it has been brought to that position by the operation of said

actuator, as long as the magnet remains active, and means for making and breaking the circuit of said magnet in cycle with the operations of said actuator.

6. The combination with a valve of intermittently operated means for opening and closing the valve, one of said means being yielding, an electromagnet arranged to exert force in opposition to said yielding means, and a switch in the circuit of said magnet intermittently opened and closed in synchronism with the operation of said valve-actuating means.

7. The combination with a valve of means for actuating the valve in one direction, yielding means tending constantly to actuate it in the opposite direction, an electromagnet arranged to apply force to said valve in opposition to said yielding means and a switch in the circuit of said magnet, means for intermittently opening and closing said switch, said means including an adjustable element, the adjustment of which varies the time in the cycle of operations during which the magnet is active.

8. The combination with a valve of an intermittently operative actuator for periodically moving the valve in one direction, a spring arranged to exert force tending to move the valve in the opposite direction, an electromagnet, the armature for which is connected to the valve, arranged to exert force on said armature in opposition to said spring, its power being sufficient to overcome the force of the spring and hold the armature when the valve is in the position wherein it is brought by said actuator, and insufficient to overcome the force of the spring when the valve and armature are in the position wherein they are placed by the free action of the spring, and an intermittent circuit breaker in the circuit of said magnet operated synchronously with said actuator.

9. The combination with a valve of an intermittently operative actuator for periodically moving the valve in one direction, a spring arranged to exert force tending to move the valve in the opposite direction, an electromagnet, the armature for which is connected to the valve, arranged to exert force on said armature in opposition to said spring, its power being sufficient to overcome the force of the spring and hold the armature when the valve is in the position wherein it is brought by said actuator, and insufficient to overcome the force of the spring when the valve and armature are in the position wherein they are placed by the free action of the spring, and an intermittent circuit breaker in the circuit of said magnet operated synchronously with said actuator, said circuit breaker including a movable contact adjustable to vary the proportion of the cycle during which said cir-

- cuit remains closed after the actuation of the valve by said actuator.
10. The combination with a valve of a rotary cam, a rotary circuit breaker associated therewith having an interrupted contact surface, a complementary contact element arranged to co-act intermittently with said surface according to the position of said breaker, an armature connected with the valve, an electromagnet in co-operative relation with said armature and in circuit with said circuit breaker and contact, and a spring arranged to exert force tending to withdraw said armature from said magnet and at the same time move the valve, the cam being arranged and operative to move the valve and armature in opposition to the force of said spring.
11. The combination with a valve of a rotary cam, a rotary circuit breaker associated therewith having an interrupted contact surface, a complementary contact element arranged to co-act intermittently with said surface according to the position of said breaker, an armature connected with the valve, an electromagnet in co-operative relation with said armature and in circuit with said circuit breaker and contact, and a spring arranged to exert force tending to withdraw said armature from said magnet and at the same time move the valve, the cam being arranged and operative to move the valve and armature in opposition to the force of said spring, said contact being adjustable along the contact face of the circuit breaker so as to vary the proportional part of the cycle during which it remains in contact therewith.
12. The combination with a valve of a stem, an armature on said stem, an electromagnet surrounding said stem in co-operative relation with the armature, a spring acting on said valve tending to remove the armature from the magnet, a rotary cam arranged to act on said stem so as to move the same in such manner that the armature is displaced toward the magnet against the resistance of the spring, and a circuit breaker interposed in the circuit of the magnet comprising complementary contacts, one of which is associated and movable with the cam, and is formed to make contact with the other during a part only of its cycle of rotation.
13. The combination with a valve of a stem, an armature on said stem, an electromagnet surrounding said stem in co-operative relation with the armature, a spring acting on said valve tending to remove the armature from the valve, a rotary cam arranged to act on said stem so as to move the same in such manner that the armature is displaced toward the magnet against the resistance of the spring, and a circuit breaker interposed in the circuit of the magnet comprising complementary contacts, one of which is associated and movable with the cam, and is formed to make contact with the other during a part only of its cycle of rotation, and one of said contact members being also adjustable to vary the part of the cycle during which such contact occurs and continues.
- In testimony whereof I have affixed my signature.

GILBERT WRIGHT.
